TUBE DISPENSER

Lyle G. Mann, Redwood City, and George T.
Dickinson, Belmont, Calif.

Application February 14, 1952, Serial No. 18,514

Term of patent 3½ years

(Cl. D4—3)

To all whom it may concern:

Be it known that we, Lyle G. Mann, and George T. Dickinson, citizens of the United States, have invented a new, original, and ornamental Design for a Tube Dispenser, of which the following is a specification, reference being had to the accompanying drawing, forming part thereof.

Fig. 1 is a front view of a tube dispenser, embodying our new design.

Fig. 2 is a side view of Fig. 1 as seen from the left side thereof.

Fig. 3 is a perspective view of the tube dispenser.

Fig. 4 is a plan view of the tube dispenser shown in Fig. 1 as seen from above; and

Fig. 5 is a bottom plan view of the tube dispenser as seen from below in Fig. 1.

The dotted line disclosure of a tube in Fig. 3 is for illustrative purposes only.

We claim:

The ornamental design for a tube dispenser, as shown and described.

LYLE G. MANN.
GEORGE T. DICKINSON.
